UNITED STATES PATENT OFFICE

CLYDE P. ROSS, OF CHICAGO, ILLINOIS

HOIST

Application filed September 20, 1926. Serial No. 136,412.

This invention relates to a feeding and hoisting apparatus and particularly to a mechanism adapted to control the flow of material into a hoisting receptacle and to do this in response to the movement of the hoisting receptacle. One object of the invention is to provide means whereby a control gate, controlling discharge of material from a fixed receptacle, is positively and automatically operated by a moving receptacle. Another object of the invention is to provide means whereby the two during their period of co-operation are locked to each other and whereby they are automatically unlocked when the receptacle has been filled and has commenced its movement. Other objects will appear from time to time throughout the specification and claim.

My invention is illustrated more or less diagrammatically in the accompanying drawings, wherein—

Figure 1 is a vertical cross section showing the bin and the bucket and a portion of the hoisting track;

Figure 2 is an enlarged cross section of a portion of the bin and bucket showing in detail the discharge orifice from the bin, and the gate mechanism;

Figure 3 is a top elevation of the gate.

Like parts are indicated by like characters throughout.

A is a loading pit formed in part by enclosing walls A¹. It is provided in this form generally so as to provide a bin and a cavity in which tracks may be positioned to carry a bucket or other moving receptacle. A² is a trough or depression formed in the sloping wall of the pit to provide room for a portion of the bucket as it moves.

B is a receiving bin extending into the loading pit and formed preferably in part of the walls A¹. Extending across it are supports B¹ which may carry tracks B². B³ indicates the contents of the bin.

Situated at the bottom of the bin is a door C. As here shown this door is formed of a metallic structure which is inserted into an opening in the bin proper. This is preferable but it is not an essential feature of the structure. The door is provided with a chute C¹

which communicates with a somewhat larger chute C². C³ is a gate or movable closure provided for the door. C⁴ is a track assembly supported in part on the frame C⁵ and partly on other frame members C⁶. C⁷ are rollers supporting the gate C³ from the track C⁴. The gate is mounted to be moved back and forth along the track by the bucket. As the bucket descends it contacts the gate and moves it downward along the track opening the door of the bin to permit discharge into the bucket. C⁸ C⁹ are angle members located on the gate and reinforcing it. Fastened to the gate and preferably pivoted to these angles is a pair of engaging latches C¹⁰. Each of them is preferably formed as shown with two side members each being inwardly bent as at C¹¹. Each of the latches has an upwardly bent portion C¹². Mounted at the inner end of the upwardly bent portion of each of the latches is a roller C¹³ and at the outer end a roller C¹⁴. On its bottom the gate is provided with bucket contacting tops or brackets C¹⁵. These brackets are shaped preferably to receive the rear edge of the bucket as it descends and contacts it. The gate is normally held closed by one or more counterweights C¹⁶ each of which is attached to a cable C¹⁷, and at its other end is fastened to the gate and passes over a sheave C¹⁸. In Figure 1 the counterweight has been omitted for the sake of clearness.

The particular details of the track structure and arrangement form no part of the present invention. It is sufficient for the purpose of the present invention that the bucket runs beneath the bin. The track structure generally consists of a pair of main double tracks D, beneath each of which is a guide track D¹. The track D extends into the pit and is joined to a track E which is in effect a continuation of it.

F is a second double track generally like the tracks D and E and it turns from the track D at a point immediately below a supporting frame member D² which member serves to position and support the tracks.

G is a frame member supporting the tracks and their several branches.

H is a bucket having on either side flanged

rollers H^1 adjacent its bottom and having also flanged rollers H^2 located higher up. H^3 is a swinging door mounted for movement on the bottom of the bucket H provided with a shaft H^4 having a pair of preferably double flanged rollers H^5 mounted on it. These rollers contact the track D^1 and throughout the major part of the excursion of the bucket prevent the door from swinging open.

10 I^1 is a contact member mounted on the bucket H adapted to contact the engaging lugs C^{15} on the gate structure. This member strikes these lugs as the bucket descends into the pit. I^2 a locking member mounted on 15 the bucket adapted to engage with the locking latches C^9 in the manner shown in Figures 1 and 2 and assist in causing the bucket and gate to move together throughout a part of their excursion. I^3 is a track member 20 adapted to be contacted by rollers C^{14} as shown particularly in Figures 1 and 2 and serving to hold the locking latch in locking position as shown in these figures. I^4 is a limiting member adapted to be contacted by 25 the rollers C^{14} and the locking latch as shown in dotted lines in Figure 2 and to co-operate thus to unlock the locking latch from the member I^2 and thereby to free the bucket and gate from each other.

30 Although I have shown an operative device, still it will be obvious that many changes might be made in size, shape and arrangement of parts without departing materially from the spirit of my invention; and I wish 35 therefore that my showing be taken as in a sense diagrammatic.

The use and operation of my invention are as follows:

This apparatus is normally part of a coal 40 or other material handling plant in which the material to be handled is transported in cars and from them dumped into a receiving bin. From this bin material is discharged periodically into a bucket which is periodically 45 raised and lowered. The load of the bucket is itself, after having been raised, discharged into some other receptacle.

When the apparatus is to be used the hoisting mechanism of the bucket is set in operation 50 and the bucket is lowered into the pit beneath the bin. The part I of the bucket contacts the lugs C^{15} of the gate and forces the gate open in opposition to the weight of the counter-weight. At the time that this action 55 commences the locking latches C^9 have each of them engaged one of the members I^2 so that the bucket and gate are locked together and move as a unit. The lowering movement of the bucket as it continues therefore 60 moves the gate with it steadily downward.

When the bucket has been loaded, it is raised and the gate moves upwardly under the influence of the counter-weight and also under the influence of the hoisting force of 65 the bucket itself because the locking latches

still hold the gate positively to the bucket. Thus it is certain that if the bucket rises, the gate will rise with it, and the locking latches are held in locking engagement with the projections on the bucket by the tracks I^3 which positively prevent displacement of the latches during this period in the operation of the device.

When the gate has been closed, that is when it has reached the full closed position due to the raising of the bucket, the forward or outward roller of each of the locking latches strikes the member I^4 and since it cannot move further in the direction of motion of the bucket, it moves upward along the direction of the member I^4 and thus it is pivoted upward about its pivot point and moved out of engagement and out of contact with the locking members I^2 , and the bucket and gate are thus separated from each other, the gate 55 to remain in closed position where it is held by the counterweight, and the bucket to continue upward.

I claim:

In combination with a hopper, a reciprocating gate, a bucket moving into and out of register with the hopper, an intermediate chute between the bucket and hopper, means interposed between the bucket and the gate for opening the latter after the bucket reaches the loading position, a latch pivoted on the gate, said latch having an up-turned end and being provided with anti-friction members, an abutment on the bucket adapted to be engaged by the latch whereby the bucket as it leaves the loading position, positively closes the gate, the latch comprising a link pivoted on the gate, tracks along which the bucket, the gate and the link travel, means including one of said tracks to hold the latch in engagement with the bucket while the bucket is in the loading position, and means comprising a track member angularly disposed with relation to the gate track for forcing the link out of engagement with the abutment when the gate has reached the closed position.

Signed at Chicago, county of Cook and State of Illinois, this 3rd day of September, 1926.
